UNITED STATES PATENT OFFICE.

PETER MAHLER, OF UTICA, ILLINOIS.

CHICKEN-BROODER.

No. 890,149.

Specification of Letters Patent. Patented June 9, 1903.

Application filed January 29, 1903. Serial No. 413,158.

To all whom it may concern:

Be it known that I, PETER MAHLER, a subject of the King of Denmark, and a resident of Utica, in the county of Lasalle and State of Illinois, have invented certain new and useful Improvements in Chicken-Brooders, of which the following is a specification.

My invention relates to brooders which are not artificially warmed.

It is designed more especially for chicks three weeks old and upward; and the objects of the improvements are: first, to provide means for enabling the chicks to safely huddle together in a coop so as to combine, 15 conserve and apply the individual warmth of their bodies for suitably warming the enclosure; second, to provide means for suitably ventilating such warmed inclosure; and third, to provide a coop structure comprising readily detachable parts in order that it 20 can be easily cleaned. I attain these objects in the brooder constructed as illustrated in the accompanying drawing in which:

Figure 1 is a top view of a brooder embodying my invention with the cover removed and a portion of an interior part broken away to show the structure at the bottom. Fig. 2 is a front elevation of the same having 30 the door removed and a portion of the front wall broken away to show the interior structure. Fig. 3 is a central vertical section from front to rear at the line 3-3 of Fig. 2.

Like signs marked on the drawing refer to 35 like parts throughout the several views.

I provide a box having a base about 32 by 33 inches, the front side being about 11 inches high and the rear 9 inches. The front wall 4 and upper part 5 of the side and rear walls 40 are made of a single thickness of board. But the lower part of the sides and rear are provided with a lining 6 set off by a cleat 7 at the top of the lining so as to form a dead air space 8 around the two sides and rear of the 45 box at the lower part thereof.

The bottom of the box is provided with cleats 9 and upon these is laid a coarse screen 10 of galv. nized wire which is of the proper size to fit loosely within the lining 6 so as to 50 fall down within the same and lie flat upon the cleats. At the front the screen preferably projects slightly over the cleats and is bent down to touch the bottom of the box as best shown in Fig. 3. The mesh of the 55 screen is about one-quarter inch more or less being suitable to form a perforated floor for

the chicks to walk upon and to allow a free circulation of air through the same. The front has an entrance and exit opening provided with a door 4^a for opening and closing 60 the same when desired.

I provide a hoverer, comprising an imperforate plate or piece of board 11, of the proper size to lie within the box and rest upon the top edge of the lining 6, but not to extend to 65 the front board 4, and having a series of strips of flannel cloth 12 secured to its inner side. The space between these strips is about 2 $\frac{1}{2}$ to 3 inches and the strips are run parallel with that side of board 11 which does not 70 meet the front wall of the box. They are provided with slits 13 from the bottom up nearly or quite to the top, the pendent individual parts between the slits being about 75 2 $\frac{1}{2}$ to 4 inches wide, and the slits of each adjacent strip preferably falling at about the center of the pendent of the next strip as indicated by broken lines Fig. 2. The bottom edge of the pendent parts is from $\frac{1}{2}$ to $\frac{3}{4}$ of an 80 inch above the upper surface of the screen 10. This hoverer with its narrow flannel pendent parts supported above the bottom of the box and within its inclosure offers no substantial 85 obstruction to the chicks going in under it and huddling there so that the heat from their individual bodies is combined, conserved, and applied to warm that portion of the inclosure formed by the lined walls and hoverer board 11 resting thereon and located over the 90 screened bottom. The pendent flannel strips 95 are slitted and arranged apart as shown are designed and adapted to part at the slits and give the greatest freedom for entrance of the chicks under the hoverer and to allow the greatest freedom of individual movement 100 when there. The pendent narrow parts of the slitted flannel strips are adapted to part for allowing the chicks to enter at the front, and to lie upon their backs and hang close to their bodies when in. In this respect my 105 hoverer is different in operation from a prior one shown in United States Patent No. 317,910 of May 5, 1885 to Rosebrook, and having a series of continuous or unslitted flannel strips of double layers arranged quite 110 close together.

The box is provided with a cover 14 adapted to fit over the top of the box and completely cover it over the entire top. The cover is detachable so that it may be easily 110 lifted off.

It is noted that the hoverer board 11 does

not extend forward to the front wall 4 of the box, but leaves from $2\frac{1}{2}$ to 3 inches more or less open space, as seen at 15, extending all along the front wall. The side walls near the 5 front wall and above the hoverer board are provided with openings 16. Through these ventilating openings 16 of about $1\frac{1}{2}$ inch diameter, in the side walls the air from the outside can enter the space under the cover 10 14 near the front wall and above the hoverer at both ends of said open space between the hoverer and the front wall and pass down through the same to the bottom of the box. When the air under the hoverer board is 15 warmed, as it will be by occupancy for a short while by a brood of chicks, a circulation will be started by the tendency of warmer air to rise up against the imperforate hoverer board which forms a tight closure of the double- 20 wall portion of the box at all points except the front, serves to prevent the warm air from rising too high above the screen floor and directs the movement of upper air stratum or warmest part toward the front. The 25 movement of the upper stratum of air under the hoverer board toward the front of the box is to the required extent checked by the depending slitted strips but it is permitted to pass out slowly into said open space at 15 and 30 thence up and out through said openings 16 while the outer cold air entering the box through said opening 16 and descending through said open space at 15 is allowed to pass slowly from the front toward the rear 35 of the box in the open space below the dependent slitted strips and under the screen 10 ultimately to rise and take the place of the foul air which has passed off from immediately below the hoverer board through 40 the slits in the pendent strips.

The air can circulate under the pendent slitted cloth strips and also under the screen floor so that if some of the chicks in the brood are knocked down and trampled on in the 45 huddle they can still breathe from the air below the screen and so will not smother.

The dimensions of brooder box and other parts given are designed and adapted to accommodate from 50 to 100 chicks three 50 weeks old, at first filling the hoverer comfortably full and afterwards reducing the number as they get larger.

According to the usual practice in raising incubator chicks they are kept in lamp-heated brooders until three weeks' old and then turned to roost without other means than the common coop to protect them from the cold. With such keeping they huddle in the coop too closely and some are suffocated 55 or hurt by being trampled on, and all suffer 60

more or less from cold. In consequence of the cold they do not thrive well and many get sick and die before they are six weeks old.

I have thoroughly tried my improved brooder for two seasons and found it well 65 adapted to the work for which it is intended. Harbored by it the chicks get very hardy and grow and thrive well, in fact a great deal better than they do in lamp-heated brooders. Particularly, it is proved that the hoverer 70 constructed as I have shown secures the safe huddling of the chicks in the coop so as to prevent their injuring one another and so as to combine and apply the warmth of their bodies for sufficiently warming the inclosure 75 for their protection from cold. It is also proved that the chicks get all the ventilation 80 they require from the front side only of the coop provided with such hoverer and having the elevated screen floor under which the air 85 can pass at the front side. The cover being lifted off, the hoverer and the screen can be taken out for cleaning the box whenever desired.

What I claim:

1. A chicken brooder comprising a box-like structure provided with an entrance opening, ventilating openings, and a detachable cover, a detachable screen floor supported above the bottom of the box, a detachable imperforate plate shorter at the front side than the box bottom and provided with a cluster of regularly-spaced narrow cloth parts pendent therefrom and facing toward the front of the box, and means 90 for supporting said plate within the box with said pendent parts clear of the screen floor and clear of the front wall of the box.

2. A chicken brooder comprising a box-like structure provided with a horizontal partition shorter at the front side than the box bottom, an entrance opening in the front side and ventilating openings above the partition in proximity to the front side, in combination with a cluster of regularly-spaced 100 cloth strips suspended from the under side of the partition and extending downwardly nearly to the box bottom, said strips being 105 extended parallel with the front wall of the box and slitted from the bottom upwardly 110 to the partition, the arrangement being such as to provide air space within the box extending horizontally under said cluster and vertically between it and the front wall of the box to the space above the partition. 115

PETER MAHLER.
